UNITED STATES PATENT OFFICE.

CHARLES CARLETON, OF LAKE, COOK COUNTY, ILLINOIS.

ATTACHMENT FOR CONNECTING COIL-SPRINGS.

SPECIFICATION forming part of Letters Patent No. 325,818, dated September 8, 1885.

Application filed March 27, 1885. (No model.)

To all whom it may concern:

Be it known that I, CHARLES CARLETON, a citizen of the United States, and a resident of Lake township, Cook county, and State of Illinois, have invented a new and useful Improvement in Attachments for Connecting Spiral Springs for Bed-Bottoms and other Purposes, reference being had to the annexed drawings, illustrating the invention, in which—

10 Figure 1 is a plan or top view of a section of the springs of a coil-spring bed-bottom combined with my improved attachment. Fig. 2 is a sectional edge view of one of the attachments with transverse sections of the springs connected by it. Fig. 3 is a plan view of the blank attachment as it is cut from sheet metal and before it is attached to the springs. Fig. 15 4 is a perspective view of the under side of the attachment shut together as when connecting the springs.

The object of the present invention is to provide simple, cheap, and safe attachments for connecting coil-springs which are used for beds, seats, mattresses, and other purposes.

25 Heretofore wire links have been used for this purpose, and webbing has also been used and the laps held together by metal clamps; also, metal straps have been employed and their lapped parts riveted together, and wires have 30 been made to engage the spring and run diagonally across the bed-bottom; and it has been the custom to connect springs by straps of fabric and clamps, the latter being cut in a cruciform shape and the wings folded on opposite sides of the center *a* thereof to clamp 35 the fabric in place where the strips cross each other.

40 My purpose is to make a bed-bottom, mattress, or seat body wholly of metal, and to connect the springs by an attachment which 45 will permit any number of springs to be compressed without the attachments acting as levers on the other springs, and at the same time hold the springs a given distance apart. This I accomplish by an attachment which is formed of a single piece of sheet metal con-

sisting of a central body part with four projecting wings, two of which are looped around the springs, and the other two shut onto the looped part, whereby the attachment forms 50 joints on the springs.

A, &c., represent a section of six springs of the ordinary hour-glass construction, which when used in this form both ends are to be connected with my attachments and used for 55 beds, lounges, or seats without a frame attachment. My attachments, however, may be used to connect the ends only of the tops of the springs, and thus be employed in connection with wooden slats or frames. The blank for 60 the attachment as cut and before connected with the springs is shown in Fig. 3, and consists of a central body, *a*, two end wings, *b b*, and two side wings, *c c*. The end wings are 65 looped over the springs A, and brought flat on to or parallel with the body part *a*, and then the side wings are brought over to lie flat on the ends of the wings *b b*, and the connections are complete.

The advantage of this attachment, aside 70 from the points mentioned, consists in the stiffness of it between the springs, and in that it serves both the purpose of two joints and a strut to hold the springs the required distance apart, and is preferable to a double loop for 75 connecting the springs, and a transverse clamp to hold the ends of the loop to its bar, a construction I have used in lieu of the one here presented.

I claim as new and desire to secure by Letters Patent—

The combination of the coiled wire springs with the connecting-plate having the wings *b*, which are looped over the coils of the springs to hold them together, and the wings *c*, bent 85 over the wings *b* to hold them and to keep the springs separated, substantially as described.

March 19, 1885.

CHARLES CARLETON.
